UNITED STATES PATENT OFFICE.

WILLIAM A. FALLS, OF DETROIT, MICHIGAN, ASSIGNOR TO L. A. YOUNG INDUSTRIES, INC., OF DETROIT, MICHIGAN.

SPRING STRUCTURE.

Application filed March 14, 1925. Serial No. 15,603.

This invention relates to improvements in spring structures.

The main objects of this invention are:

- 5 First, to provide in a spring structure an improved supporting base which effectively supports the springs and which is also well adapted for the attachment of upholstery thereto, the upholstery being protected from wear.
- 10 Second, to provide an improved spring structure having a very rigid frame which is at the same time compact and affords an effective means for attachment of the upholstery.

15 Objects pertaining to details and economies of my invention will definitely appear from the detailed description to follow.

I accomplish the objects of my invention by the devices and means described in the 20 following specification. The invention is clearly defined and pointed out in the claims.

A structure embodying the features of my invention is clearly illustrated in the 25 accompanying drawing forming a part of this application, in which:

Fig. I is a fragmentary vertical section of a structure embodying the features of my invention.

30 Fig. II is an enlarged fragmentary vertical section illustrating structural details.

Fig. III is a fragmentary perspective view of a slightly modified form of base or border frame.

35 In the drawing similar reference numerals indicate similar parts in all of the views.

Referring to the drawing, 1 represents the body springs, the structure illustrated being 40 what is known as a double deck structure. The springs are illustrated conventionally.

The springs are supported by a base comprising a border frame designated by the numeral 2 which is of sheet metal folded or 45 conformed to provide a downwardly facing channel 3 in which the tacking strip 4 of wood, fiber or other material is arranged and an inwardly facing channel 5 which is clamped upon the bottom coil 6 of the border springs. The channel 5 is formed by folding the web portion 7 of the strip upon itself.

The tacking strip is retained by the flat 55 inturned front flange 8 and the curved rear or inner flange 9, this flange 9 being of such

depth as to provide a supporting bead for the frame.

The upholstery designated generally by the numeral 10 is provided with a skirt portion 11 which is wrapped upon the frame 60 and secured thereto by the tacks 12 driven into a tacking strip. The edges of the skirt lie at the outside of the bead flange 9 and are protected thereby, this bead flange 9 also serving to support the frame so that 65 the upholstery does not contact therewith, thus preventing wear of the upholstery.

In the modification shown in Fig. III the inner flange 13 is flat to correspond with the outer flange 8. This structure does not 70 have the advantage of the protection of the upholstery but is satisfactory for some uses. The structure of Fig. II is, however, the preferred construction in that the upholstery is protected and the frame is some- 75 what stronger.

My improved spring structure is very strong and rigid and at the same time is compact. This is particularly desirable 80 owing to the present aim or tendency of doing away with seat frames in automobiles and to provide very low bodies.

I have illustrated my improvements in a simple embodiment. I have not attempted to illustrate or describe certain embodiments 85 or adaptations which I contemplate as I believe the disclosure made will enable those skilled in the art to embody or adapt my improvements as may be desired.

Having thus described my invention what I claim as new and desire to secure by Letters Patent is:

1. The combination in a structure of the class described with a plurality of body springs, of a supporting base therefor comprising a border frame of sheet metal conformed to provide a downwardly facing channel having an inturned flat flange at its front edge and a curved flange at its inner edge providing a bead-like support, the web portion of said strip folded upon itself 95 providing an inwardly facing channel within which the bottom coils of said springs are clamped by the said reversely folded portion thereof, a tacking strip secured within said channel by its said flanges, and an upholstery covering comprising a skirt portion wrapped upon said border frame and tacked to said tacking strip with its edges at the outside of said flange which constitutes a 100 105 110

guard therefor and a support for the frame. 2. The combination in a structure of the class described with a plurality of body springs, of a supporting base therefor comprising a border frame of sheet metal folded to provide a downwardly facing bottom channel and an inwardly facing top channel, said top channel being clamped upon the said springs, a tacking strip arranged 10 within said bottom channel and retained therein by inturned flanges at the edges of the bottom channel, the inner flange being

conformed to provide a support for the frame projecting below the plane of the outer flange, and an upholstery covering 15 comprising a skirt portion wrapped upon said frame and secured to said tacking strip, said support being adapted to support said frame in elevated position and constituting a guard for said upholstery. 20

In witness whereof I have hereunto set my hand.

WILLIAM A. FALLS.
